GEARING

Application filed December 30, 1930. Serial No. 505,590.

My invention relates to gears, more particularly of the marine reduction gear type, and it has for an object to provide a relatively strong and light driven gear.

5 A driven gear of marine reduction gearing, or of gearing where large powers are transmitted, usually comprises a web or spider structure carrying toothed rims. Ordinarily, the webs or spiders are cast. To 10 provide a lighter and stronger construction, I provide a fabricated center, spider or web construction in which the elements are fabricated from plate stock and connected together, the elements being so cut, shaped and 15 joined together that the objectives of strength and lightness, coupled with more reliable physical properties inherent in the material, are realized. More particularly, the gear center or web comprises end web constructions, each including joined webs including a frusto-conical web, and a central web construction including frusto-conical webs having their apical ends joined together and having their basal edges connected to the basal 20 edges of the frusto-conical webs of the end constructions, the outer edges of the outermost webs of the end constructions and the adjacent junction portions of frusto-conical webs of end and central constructions comprising supporting portions for the rims, struts preferably extending from either side of the junction of the inner frusto-conical webs of the central web construction to the 25 end web constructions so that the sets of struts will be substantially in the conical surfaces 30 extended of the conical web elements of the central web construction. With this arrangement of web elements, it is possible to have welded joints between the webs and 35 between the webs and the rims. Not only is this type of center or web construction conducive to strength and lightness, but these effects are furthered by having the webs joined to the rim so that the latter is deflected a minimum under load, whereby the rim 40 may be made of minimum weight as minimum stiffness is required under the minimum deflection condition. A further object of my invention is to provide these advantageous 45 features of construction, as well as the meth-

od followed, making it possible to fabricate a relatively light and strong gear, particularly the web construction or spider thereof.

A further object of my invention is to provide an improved method of gear manufacture, the rim or rims being welded to the center or web construction and the assembly being annealed prior to cutting of teeth in the rims. More particularly, the steps just referred to are preferably preceded by steps 55 of center or web construction, namely, forming the end web constructions of connected web elements; forming the central web construction of connected frusto-conical web elements; in arranging the central web construction between the end web constructions; in welding together the basal edges of adjoining frusto-conical web elements of the end and central web constructions; in welding 60 the apical ends of the frusto-conical web 65 elements of the end constructions to the outermost web elements thereof; in welding the apical ends of the frusto-conical web 70 elements of the central web construction together; in welding struts to the end web 75 constructions adjacent to the apical ends of the frusto-conical web elements thereof and to the central web construction in the vicinity 80 of the joined apical ends thereof; in annealing the fabricated center or web construction; in providing rims of slightly less internal diameter than the diameter of the end and central web constructions; in heating the rims so that the latter may pass over the radial web element of the end web construction and the adjoining basal edges of the frusto-conical web elements of the end and central web constructions; in annealing the 85 assembled rim and web assembly; and in cutting teeth in the rims. Preferably, teeth are 90 rough cut after annealing following welding of the rim or rims and then a second step of annealing is resorted to before finish cutting of the teeth. Hence, a further object of 95 my invention is to use the method steps referred to in gear manufacture.

These and other objects are effected by my invention as will be apparent from the following description and claims taken in connection with the accompanying drawings, 100

forming a part of this application, in which:

Fig. 1 is a sectional view of my improved gear and taken along the line I—I of Fig. 2;

Fig. 2 is a sectional view taken along the line II—II of Fig. 1;

Fig. 3 is an exploded view showing the gear rims and component elements of the center; and,

Figs. 4 to 7, inclusive, are detail sectional views of web connections.

Referring now to the drawings more in detail, I show a driven gear having a pair of toothed rims 10 carried by a fabricated center, at 11, connected to the shaft 12.

The fabricated center is made up of end web constructions, at 13, and a central web construction, at 14. Each end web construction includes an outermost web 15 and a frusto-conical web 16 having an apical flange 17 connected to the web 15. The outermost web 15 is preferably radial, as shown, but it might be shaped otherwise so long as it is capable of achieving its purpose and is related to the other elements in substantially the same manner. The central web construction, at 14, consists of frusto-conical webs 18 having abutting apical flanges 19. The basal edges 21 and 22 of the webs 16 and 18, respectively, are of the same diameter as the end webs 15 and such basal edges are joined together. Each rim 10 encompasses and is joined to an end web 15 and the adjacent joined basal edges 21 and 22 of the frusto-conical webs 16 and 18.

The apical annular flanges 19 are of larger diameter than the flanges 17 and struts 23 are connected to the end web constructions, at 13, in the region of the flanges 17 and to the central web construction, at 14, in the region of the joined apical flanges 19.

From the structure described, it will be apparent that a gear having a center of this character, while relatively light, is strong and stiff and resists deflection or deformation of any character. The frusto-conical webs 16 brace the inner portions of the rims 10. Also, the struts 23 serve to stiffen and strengthen the construction, the struts preferably being arranged in conical sets approximately in the conical surfaces extended of the frusto-conical webs 18 so as to be capable of acting effectively to brace the gear rims. Furthermore, the joint between the outermost web 15 and the rim 10 and the joint between the joined basal edges 21 and 22 of frusto-conical webs and the rim 10 are so spaced axially with respect to the rim that the deflection of the latter is at minimum under uniformly distributed load. In other words, the joints are each spaced apart a distance which is approximately $\sqrt{6}$ times the overhang distance at either end. Due to supporting of the rim for minimum deflection, the stiffness required is reduced to a mini-

mum and, therefore, the rim may be made of minimum weight.

In order that the gear center 11 may be assembled and rigidly connected to the shaft 12, the latter is provided with cylindrical seats 24 and 25 and with adjacent flanges 26 and 27, the seat 25 being of a diameter at least as great as the diameter of the flange 26 and the shaft opening 28 of one end web construction, at 13, being larger than the opening 29 of the other so that the larger opening may pass over the flange 26 and fit the cylindrical seat 25.

Bolts 31 connect the end web constructions, at 13, to the flanges 26 and 27. As a larger number of bolts connect the flange 27 to the adjacent end web construction, at 13, than connect the flange 26 to the other end web construction, the latter has preferably connected thereto an end reinforcing plate 32.

The outer and frusto-conical web elements 15 and 16 of the end web constructions, at 13, are preferably connected by rivets 33, and the central web construction, at 14, has the apical flanges 19 thereof connected together by bolts 34. In this way, the three component elements of the gear center are first constructed or assembled, the web elements 15 and 16 of each end web construction, at 13, being riveted together and the frusto-conical web elements 18 of the central web construction being bolted together.

The end and central web constructions, at 13, and 14, are axially aligned or superposed and welded, the adjoining basal edges 21 and 22 being welded together as shown at 35w (Figs. 1 and 7); the apical flanges 17 being circumferentially welded at the inner and outer margins thereof to the adjacent outer web 15 as shown at 36w and 37w (Figs. 1, 4 and 6); and the abutting apical flanges 19 having their inner and outer margins welded together as shown at 38w and 39w (Figs. 1 and 5). As already pointed out, the apical flanges 19 are of larger diameter than the flanges 17 and the struts 23 have their ends welded, as shown at 40w, to the flanges 17 in the vicinity of the junction of the latter with the body portion proper of the frusto-conical webs 16 and the other ends of the struts 23 are welded, at 41w, to the central web construction, at 14, in the vicinity of the junction of the apical flanges 19 with the body portions proper of the frusto-conical webs 18. The toothed rims are welded at 42w and 43w to the outer webs 15, the welds 42w and 43w preferably being staggered, and it is welded at 44w and 45w to the frusto-conical webs 16 and 18, respectively, the welds 44w and 45w being discontinuous and staggered with respect to the discontinuous welds 35w.

In manufacturing my improved gear, the shaft 12 is provided with the seats 24 and 25 and adjacent flanges 26 and 27 of desired sizes. The web elements are cut and shaped from

suitable steel plates with openings including the shaft openings provided in the web elements 15 and 16. The web elements 15 and 16 are riveted together to form the end web constructions, at 13. The web elements 18 of the central web construction, at 14, are connected together by the bolts 34. The two end web constructions, at 13, and the central web construction, at 14, are then brought together in axial or superposed relation, the basal edges 21 and 22 of the web elements 16 and 18 being welded together, as shown at 35w. Thereafter, the apical flanges 17 are welded at 36w and 37w to the end webs 15 and the apical flanges 19 of the central web construction have their inner and outer margins welded together at 38w and 39w. Also the struts 23 are welded to the end and central web constructions, at 13 and 14, as already pointed out.

The assembled web construction, at 11, is then annealed, preferably at a temperature of 1000 degrees F., in order to relieve stresses due to fabrication, particularly, those due to the welding operations, this temperature being low enough not to affect desired physical properties of the steel. Next, the center is turned in order to true up the circumferential web edges, and the rims 10 are bored to slightly smaller diameter than the diameter of the web edges. The rims are heated just sufficiently to expand them so that they will pass over the web edges, it being possible to do this without heating the rims to such a temperature as to disturb their physical properties. After the rims are in place, they are welded, as shown at 42w, 43w, 44w, and 45w to the webs 15, 16, and 18; and, after welding, the assembled structure is subjected to a second stage of annealing, as before, preferably at 1000 degrees F., which is low enough not to affect the desired physical properties. Thereafter, the gear wheel is rough machined, material being left for finish machining, and the teeth are rough cut. Preferably, after these rough machining operations, the gear is subjected to a third stage of annealing at the same temperature as before, the second and third stages of annealing assuring that any stresses set up in the rim on account of welding, machining, or contraction against the web edges shall be relieved, while retaining desired physical properties. If there should be locked-up stresses in the rims relieved by rough cutting and causing distortion, or if stresses should be set on account of such cutting or machining, then the third step of annealing provides for relief of stresses prior to finish machining or cutting with the assurance of a stable final tooth form. It is to be understood, however, that the third stage of annealing may be omitted, as the second stage may be quite sufficient to relieve stresses set up on account of welding the rims to the webs; however, as a matter

of precaution, I prefer to subject the structure to the third stage of annealing.

The bolts connecting the web elements 18 of the central web construction, at 14, are removed and the holes are reamed, so as to provide for drive fits of slightly larger bolts. Thereafter, the wheel structure is finished bored, the bolting faces of the end web constructions are finished, and such constructions are bolted to the flanges 26 and 27. The shaft 12 with the gear mounted thereon and connected thereto is now turned so that the tips of the gear teeth will all be in a cylindrical surface which is coaxial with the axis of the shaft 12 and the teeth are finished.

From the foregoing, it will be apparent that I have devised a gear of the marine reduction type which is strong and light. Strength with lightness is secured by forming the center or web construction from steel plate and by having the gear rims connected to the center or web construction in such a way that each rim is subjected to minimum deflection under load. As already pointed out, minimum deflection of a gear rim, which, of course, has uniformly distributed load imposed thereon, supported at two axially spaced points or regions, occurs when the distance between the supporting regions is equal approximately to the product of

$\sqrt{6}$

times the overhang distance. With minimum deflection provided for in this way, it is obvious that minimum stiffness is required on the part of the rim for satisfactory operation, and, therefore, the weight of the rim may be reduced to a minimum. Aside from the advantageous features of strength and lightness following from the fabricated type of center or web construction, on account of the manufacture of the latter from steel plate, the material is more dependable and its physical properties are more uniform.

Also, the web elements of the center or web construction are of such design and are so disposed relatively, that maximum stiffness and strength are secured. Furthermore, I have devised a novel method involving the fabrication and assembly of the gear parts and steps of annealing, including annealing of the gear rims to remove stresses and to assure minimum distortion of finished gear teeth.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. In a gear, a pair of toothed rims and

a web structure for supporting the rims, the web structure including outer webs having their peripheries joined to the rims adjacent to the outer ends of the latter, frusto-conical

75 webs having their outer edges respectively joined to the rims adjacent to the inner ends of the latter and having their inner edges joined together, and conical sets of stress members connected to the conical webs adjacent to the junction thereof and connected to the outer webs.

2. In reduction gearing, a shaft, a pair of spaced outer webs, a pair of toothed gear rims encompassing the webs and joined to the latter at outer end regions of the rims, bracing webs connected to the gear rims at regions adjacent to inner ends thereof and extending inwardly toward the respective outer webs and connected thereto to form inner junction portions, means for connecting the junction portions to the shaft, and cross-bracing means connected to the inner end portions of the rims and to said junction portions.

3. In reduction gearing, end web constructions each including an outer web and an inner frusto-conical web having its central portion connected to the outer web, a central web construction including a pair of frusto-conical webs having their apical ends connected together and having their basal edges disposed adjacent to the basal edges of said inner frusto-conical webs, a toothed gear rim encompassing each outer web and the adjacent pair of basal edges of frusto-conical webs, and means providing junction connections between the gear rims and the outer webs and between the gear rims and the adjacent basal edges of the frusto-conical webs.

4. In reduction gearing, end web constructions each including an outer web having a central shaft opening and an inner frusto-conical web having a central flange portion provided with a shaft opening registering with the radial web shaft opening and the flange portion being connected to the outer web, a central web construction including a pair of frusto-conical webs having adjacent apical portions connected together and having their basal edges disposed adjacent to the basal edges of said inner frusto-conical webs, a toothed gear rim encompassing each outer web and the adjacent basal edges of frusto-conical webs, means providing junction connections between the gear rims and the outer webs and between the gear rims and the adjacent basal edges of the frusto-conical webs, and stress members joining the connected portions of the webs of the end web constructions and the connected apical portions of the webs of the central web construction.

5. In reduction gearing, end web constructions each including an outer web having a central shaft opening and an inner frusto-conical web having a central apical flange abutting the outer web and provided with a

shaft opening registering with the outer web shaft opening and means for connecting the flange portions to the outer webs including rivets and inner and outer circumferential welds between the margins of the flange portions and the outer webs; a central web construction including a pair of frusto-conical webs having abutting apical flanges and having their basal edges arranged in abutting relation with respect to the basal edges of the inner frusto-conical webs, means for connecting the abutting apical flanges including circumferential welds; and a toothed gear rim encompassing each outer web and the adjacent joined basal edges of frusto-conical webs and welded thereto.

6. In reduction gearing, end web constructions each including an outer web having a central shaft opening and an inner frusto-conical web having its central portion connected to the outer web, a central web construction including a pair of frusto-conical webs having their apical ends connected together and having their basal edges connected to the basal edges of said inner frusto-conical webs, strut means connected to the end web constructions at the junction regions of the webs thereof and connected to the central web construction at the apical junction region thereof, and a toothed gear rim encompassing each outer web and the adjacent joined basal edges of frusto-conical webs and joined thereto.

7. In reduction gearing, end web constructions each including an outer web having a central shaft opening and an inner frusto-conical web having an apical flange opening registering with the shaft opening of the outer web, means for connecting the apical flanges to the outer webs including circumferential welds between the inner and outer margins of the flange portions and the outer webs; a central web construction including a pair of frusto-conical webs having abutting apical flanges of larger diameter than the first apical flanges, means for connecting the abutting apical flanges including inner and outer circumferential welds connecting the margins thereof; the basal edges of the frusto-conical webs of the central web construction being welded to the basal edges of the frusto-conical webs of the end web constructions; strut means welded to the end web constructions in the vicinity of the apical flanges thereof and welded to the central web construction in the region of the connected apical flanges thereof; and a toothed gear rim encompassing each outer web and the adjacent joined basal edges of frusto-conical webs of the end and central web constructions and welded thereto.

8. In reduction gearing, a shaft having spaced cylindrical seats and adjacent flanges, the seats and flanges being similarly disposed and one of the seats being of a diameter

at least as great as the diameter of the flange adjacent to the other seat; end web constructions each including an outer web having a central shaft opening and an inner frusto-conical web having an apical flange portion provided with a shaft opening registering with the outer web shaft opening and the flange portion being connected to the outer web; the shaft openings in said end web constructions having such diameters that one fits one of said seats and the other fits the other of said seats; a central web construction including a pair of frusto-conical webs having adjacent apical flanges connected together and having their basal edges disposed adjacent to the basal edges of said inner frusto-conical webs; a toothed gear rim encompassing to each outer web and the adjacent joined basal edges of the frusto-conical webs, and means providing junction connections between the gear rims and the outer webs and between the gear rims and the adjacent basal edges of the frusto-conical webs.

In testimony whereof, I have hereunto subscribed my name this 19th day of December, 1930.
